UNITED STATES PATENT OFFICE.

EDWIN R. STANDFIELD AND WILLIAM BREW, OF CHRISTCHURCH,
NEW ZEALAND.

HAT-SECURING APPARATUS.

SPECIFICATION forming part of Letters Patent No. 573,492, dated December 22, 1896.

Application filed July 11, 1896. Serial No. 598,907. (No model.)

To all whom it may concern:

Be it known that we, EDWIN ROBERT STANDFIELD, medical electrician, and WILLIAM BREW, engineer, subjects of the Queen of Great Britain, residing at 71 Cathedral Square, Christchurch, in the provincial district of Canterbury, in the Colony of New Zealand, have invented an Improved Apparatus for Securing a Lady's Hat, Bonnet, or the Like to the Head of the Wearer, of which the following is a specification.

This invention provides a simple apparatus for securing a lady's hat, bonnet, or the like to the head of the wearer through the medium of the hair, which will not necessitate puncture of the trimming, will be readily adjustable within and removed from a hat, and which will not ruffle the hair.

In the drawings, Figure 1 is an elevation of the fastener made of wire. Fig. 2 is a perspective view showing the fastener of flat metal. Fig. 3 shows the device within a hat.

It consists of a steel spring *a*, which is preferably flat and furnished with points *b* *c* at each extremity, which are at right angles to and either formed integral with the spring or made separately and secured to it by any convenient means. A piece of sheet metal *d*, provided with points *e* *f*, is clasped round and fastened to the spring *a* and forms a bracket or support, to which is pivoted the hair-grip *g*, which is preferably formed of two wires, bent as shown in the drawings, connected by solder at *g'*. The wire finger-loops *h* *i* are pivoted by metal clips *j* to the spring *a*, so as to permit of their being folded parallel with the spring or turned at right angles thereto.

The pin *k* is provided with a head *l* at one end and a smaller head *m* at the other and slides through a loop *n* at the end of the elastic *o*, which latter passes through the finger-loop *i*, the wire guide-eye *p*, which is provided upon the bracket *d*, and is secured to the hair-grip *g*. A similar piece of elastic *r* is also secured to the hair-grip at one end and after passing through the eye *p* and the finger-loop *h* terminates with a loop *s*.

In operation the finger-loops *h* *i* permit the

spring *a* to be conveniently bent between the finger and thumb into the required curve to 50 pass into the crown of the hat, within which it is maintained by the points *b* *c* and *e* *f*. The finger-loops may then be folded up and the hat passed on to the head from the front, the hair-grip *g* engaging in the hair. The 55 small headed end of the pin *k* is passed through the hair at the back from one side and slipped through the loop *s* at the end of the elastic *r* upon the other and is passed through the hair in a position which will put 60 a slight pull upon the pieces of elastic *o* and *r*. By arranging the pin to slide in the loop *n* it is more readily passed through the hair in the correct position than if it were rigidly secured to the end of the elastic *o*. 65

The smaller head *m* is of a size to permit its easy passage through the hair while it is large enough to prevent the loop *s* upon the elastic *r* from slipping off.

What we claim as our invention, and desire 70 to secure by Letters Patent, is—

1. In apparatus for securing a hat or the like to the head of the wearer, a removable bar of spring material capable of being bent so as to pass within the crown of the hat and 75 to expand therein said spring-bar being of less length than the circumference of the hat whereby it expands to fit a portion of the inside curve thereof, pointed projections carried by said bar adapted to engage the inner 80 surface of the hat to retain it in position, and the hair-grip pivoted to the front of said spring-bar and projecting rearwardly to engage the hair of the wearer, substantially as described. 85

2. In combination with a spring-support adapted to be fitted to the inside of a hat, a hair-grip carried thereby, an elastic also supported by the spring, a pin in one end of the elastic and a loop on the opposite end, substantially as described. 90

EDWIN R. STANDFIELD.

WM. BREW.
